TORSION GRIP CONTACT

Frank M. Clement, Beloit, Wis., assignor to The
Torsion Grip Manufacturing Company, Chi-
cago, Ill.

Application September 25, 1937, Serial No. 165,663

5 Claims. (Cl. 173—328)

This invention relates to electrical contact means of connectors of the general type disclosed in my copending application No. 53,220 filed December 6, 1935, and to a method of making my improved form of connector, herein described, more particular reference being had to a spring metal product such as referred to adapted to be punched and formed from sheet steel or the like.

Some of the objects of my invention are to provide a stronger and more durable connector according to size and weight; to provide a folded metal connector of this sort having a greater length of necessary fold or sharply bent part and hence greater strength; and to provide a better method or process for making such connectors.

This invention is illustrated by the accompanying drawing, in which:

Fig. 1 represents a strip of spring sheet metal stock and a pair of flat blanks punched from said strip.

Fig. 2 is a plan of one of the blanks shown in Fig. 1 on which the operation of bending over and forming the spring contact arms has been performed, the left arm being turned upward, and the right arm being turned downward.

Fig. 3 is a somewhat enlarged view of the blank shown in Fig. 2 showing a stage of the next operation which consists in turning the right half of the blank upwardly and over against the left half of the blank.

Fig. 4 is a greatly enlarged view of the device of Fig. 3 with the folding operation completed and with the contact arms arranged to form a socket.

Fig. 5 is an edgewise view of the device of Fig. 4 with the right part bent upwardly and inclined to the right, ready for assembly with similar devices on a mounting plate such as shown in Fig. 6.

Fig. 6 is a bottom view of a multiple pronged radio tube socket plate with four connectors mounted thereon and showing the apertures for mounting four more such connectors.

Referring to Fig. 1 the sheet spring metal blank 1 is fed into a punch-press adapted and operated to form punchings 2 such as are shown at the right of this view.

Each of these blanks 2 is generally rectangular and somewhat oblong in shape, with a narrowing connecting part 3 for the right and left halves 2' and 2'' respectively as viewed in Fig. 1, so positioned that when the blank is folded on its middle longitudinal axis 2a the fold will come at this point.

Each half of this blank has parts cut away

adjacent the upper left hand corner as at 4 and 5 so as to provide a leftwardly projecting arm 6 and 7. These arms ultimately cooperate to form and serve as a spring socket 8 to embrace a connector plug not shown, as will be apparent. The lower left hand corner of the blank is cut away as at 9 so as to leave the corresponding part 10 of the right half in a form adapted to serve as a terminal for connection to a wire conductor (not shown). This form of blank is apparent from both Figures 1 and 2.

Referring now to Fig. 2 the left arm 7 is shown turned upwardly and the right arm 6 is turned downwardly, so as to assume a cooperative socket forming position when the right and left halves 10 of the blank are folded as illustrated by Figs. 3 and 4.

Referring to Fig. 3 it will be apparent that when the right half 2' is folded over, on the middle longitudinal axis 2a of the blank, the upper 20 half of said right blank swings over the arm 7 of the left half 2'' and that as the folding is completed the right arm 6 swings around to an upstanding position parallel with and to the left of the original left arm, as appears in Fig. 4.

Referring further to Fig. 4, this folded blank is now ready for bending transversely, near its middle, as at 12, to form 13 shown in Fig. 5, a further slightly reverse bend at 14 being desirable, the lower part 15 being nearly vertical and the upper part 16 being more inclined.

These terminals 13 are adapted to be assembled on perforated socket plates 17, such as shown in Fig. 6, as will be understood.

It is to be understood that some of the details set forth may be altered or omitted without departing from the spirit of the invention as defined by the following claims.

I claim:

1. A torsion grip contact comprising an oblong body of resilient sheet metal having a lateral longitudinal fold line and forming two leaves in part at least disposed in substantial parallelism and each lying in a substantial common plane, one leaf having a wire receiving terminal at one end, and the opposite end thereof and the corresponding end of the other leaf being formed to jointly constitute a resilient prong receiving socket extending substantially perpendicularly to the parallel portions of the leaves to receive and embrace a contact pin thrust axially into said socket.

2. A two-leaf torsion grip contact comprising an oblong body of resilient sheet metal having a lateral longitudinal fold line and forming two

leaves in part at least disposed in substantial parallelism and each lying in a substantially common plane, one resultant leaf having a wire receiving terminal at one end and the opposite end thereof and the corresponding end of the other leaf being formed to jointly constitute a prong receiving resilient socket extending substantially perpendicularly to the parallel portions of the leaves to receive and embrace a contact pin thrust axially into said socket, said leaves being cut apart at their socket end and integrally joined at their opposite end along said fold line.

3. The method of making a contact which consists in die-stamping a blank from spring sheet-metal, said blank being nearly square with a coplanar terminal projecting at one corner and with coplanar arms remote therefrom, one on the outer edge of a half of said blank and the other on the inner edge of the complementary half, bending these arms oppositely and perpendicular to the plane of said blank and also bending each of said arms somewhat cylindrically to face oppositely on their concave sides, then bending said blank on its middle axis bordering said halves to bring the cylindroconcave faces of said arms opposite and adjacent to each other and thereby forming the complementary arms a socket adapted to receive a terminal rod and together bending the two resulting adjacent leaves of the device on a medial transverse axis to incline the socket part toward the opposite end of the device.

20 4. The method of making a contact which consists in die-stamping a generally rectangular blank from spring sheet-metal, said blank being formed with a foldline and with cut-out indentures on the two halves respectively, those on one half being on the edge next to the foldline and those on the other half being away from the foldline, said indentures being formed to provide two parallel arms coplanar with said blank and disposed crosswise of the foldline cylindrically curving said arms oppositely, bending said arms oppositely and perpendicular to the general plane of said blank, and bending said blank on said foldline to bring said halves together and with said arms in complementary socket-forming relation.

5 with coplanar arms remote therefrom, one on the outer edge of a half of said blank and the other on the inner edge of the complementary half, bending these arms oppositely and perpendicular to the plane of said blank and also bending each of said arms somewhat cylindrically to face oppositely on their concave sides, then bending said blank on its middle axis bordering said halves to bring the cylindroconcave faces of said arms opposite and adjacent to each other and thereby 10 forming the complementary arms a socket adapted to receive a terminal rod and together bending the two resulting adjacent leaves of the device on a medial transverse axis to incline the socket part toward the opposite end of the device.

15 5. The method of making a contact which consists in die-stamping a generally rectangular blank from spring sheet-metal, said blank being formed with a foldline and with cut-out indentures on the two halves respectively, those on one half being on the edge next to the foldline and those on the other half being away from the foldline, said indentures being formed to provide two parallel arms coplanar with said blank and disposed crosswise of the foldline cylindrically curving said arms oppositely, bending said arms oppositely and perpendicular to the general plane of said blank, and bending said blank on said foldline to bring said halves together and with said arms in complementary socket-forming relation.

FRANK M. CLEMENT.
